VACUUM-BOTTLE.

1,113,357.

Specification of Letters Patent. Patented Oct. 13, 1914.

Application filed September 16, 1913. Serial No. 790,020.

To all whom it may concern:

Be it known that I, JOSEPH F. LAMB, a citizen of the United States, and a resident of New Britain, in the county of Hartford and State of Connecticut, have invented certain new and useful Improvements in Vacuum-Bottles, of which the following is a specification.

The object of this invention is to produce 10 vacuum bottles having certain new and useful features of construction.

The drawing is a central vertical section of a bottle embodying my invention.

Heretofore there has been considerable 15 difficulty experienced in properly supporting the two walls of the bottle from one another at or near the bottom, such a support being necessary in order to avoid breakage which would otherwise result. It has been 20 customary to make the two walls which constitute the double-walled structure and from between which the air is exhausted, as nearly parallel as possible, but experience shows that due to unequal expansion and contraction it is almost impossible to space those 25 two walls apart a definite amount. This variation becomes troublesome when the supports are inserted, which is done before the bottom of the outer bottle is closed in, and 30 it has been necessary to carefully change the thickness of the supports or to indent the other wall of the bottle to a greater or less extent until it was pressed down upon the support. The first method consumed consider- 35 able time, and was a slow, tedious and expensive process. The second method draws the glass, thinning the wall around the indentations, making it more liable to crack or break at these points.

40 In accordance with my invention I incline one of the walls *a* relative to the other *b*, so that these walls are non-parallel and

diverge toward the bottom of the bottle. In the drawings I have shown the lower part of the inner wall tapered slightly. The amount of this incline need not be great, and no more than enough to offset any variations which may be caused by uneven expansion and contraction of the glass. The supports *c* can now all be made of a uniform thickness which may be entered between the two walls at the point of their greatest divergence, and crowded up into position until they properly support the two walls one from another. By this means patching and fitting of the supports is entirely obviated, as is the necessity of indenting the outer bottle in order to make it contact with the support, the result being that neither of the walls is weakened and the expense of manufacturing is considerably reduced and the rate of production increased.

I claim as my invention:

1. In a device of the character described, a double-walled structure provided with side walls which are plain cylinders, and curved end portions, said side walls being non-parallel, and supports insertible between the non-parallel portions of said walls and adapted to be wedged into contact with both 70 walls.

2. A vacuum insulated container comprising a double-walled structure, the sides of which are plain cylinders non-parallel throughout at least a part of their length, 75 and supports insertible between the non-parallel portions of said walls and movable toward the converging parts thereof to space said walls one from the other.

JOSEPH F. LAMB.
